UNITED STATES PATENT OFFICE.

OSCAR C. KAVLE, OF SYRACUSE, NEW YORK, ASSIGNOR TO HARVEY A. MOYER AND EMMIT G. LATTA, OF SYRACUSE, NEW YORK.

TYPE-WRITING MACHINE.

No. 830,480.

Specification of Letters Patent.

Patented Sept. 4, 1906.

Application filed June 7, 1905. Serial No. 264,150.

To all whom it may concern:

Be it known that I, OSCAR C. KAVLE, of Syracuse, in the county of Onondaga, in the State of New York, have invented new and useful Improvements in Type-Writing Machines, of which the following, taken in connection with the accompanying drawings, is a full, clear, and exact description.

This invention relates to certain improvements in type-writing machines of the class commonly known as "front-strike" or "visible-writing" machines, and refers more particularly to the paper-holding and alining mechanism as associated with a vertically shiftable platen.

My first object is to provide suitable line-indicator plates which are adjustable vertically with the platen and not only maintain a fixed relation to the printing-line in printing with lower or upper case type, but also serve as a means for pressing the paper lightly against the platen at the printing-line and also to facilitate the lining up of ruled or blank forms, so that the printed matter may be accurately alined.

A further object is to utilize these indicator-plates to determine the exact position of any particular letter or space with reference to the printing-point and to press the paper against the platen at the printing-line close to and at opposite sides of the printing-point.

Another object is to provide individual paper-holders which may be adjusted lengthwise of the platen and to mount these holders in such manner that their upper ends may be thrown forwardly individually or simultaneously and held in this position to allow corrections or erasures to be made on each copy of manifold-work without liability of displacing such copies in the machines. In other words, my purpose is to mount the paper-holders upon a rock-shaft below the printing-line and at the front of the platen and to arrange these holders so that they may be thrown forwardly and downwardly, leaving the printed part of the sheet entirely free to be turned or folded forwardly to facilitate the work of corrections or erasures.

Other more specific objects and uses will be brought out in the following description.

In the drawings, Figures 1 and 2 are respectively front and end elevations of a platen and its carriage and the various parts of my invention associated therewith, and includ-

ing particularly the paper-holding devices and indicator-plate. Fig. 3 is an end view of the platen, showing one of the paper-holding devices and its supporting-rod. Fig. 4 is a sectional view taken on line 4-4, Fig. 1, showing the same parts as seen in Fig. 3. Fig. 5 is a front face view of a modified form of paper-holder and index-plate. Fig. 6 is a sectional view taken on line 6-6, Fig. 5, showing in addition the platen.

A represents a vertically-shiftable carriage-supporting frame of a front-strike type-writing machine, and although my present invention may be used in connection with any kind of a supporting-frame which is vertically shiftable I prefer to use an oscillatory frame, as shown in Fig. 2, such frame being provided with rearwardly-extending arms *a*, which are pivoted at *a'* at the rear of a suitable platen *B* upon any available part of the main supporting-frame *C*, only a portion of which is shown in Fig. 2. This oscillatory frame *A* is provided with a track *A'* some distance in front of its pivot *a'* and parallel with the axis of the platen *B*, said track having a suitable ball-race *1* running along its top edge for receiving suitable ball-bearings *2* and is also provided with one or more ball races or pockets *3* opening from its front face near the bottom of the track for receiving and retaining ball-bearings *4*, which latter protrude slightly beyond the open side of the ball races or pockets *3*.

A platen-supporting carriage *D* is supported upon the ball-bearings *2* and *4* and is provided with a lengthwise hood *5*, overhanging the ball-race *1* and having a lengthwise groove on its inner face for receiving and forming a bearing for the ball *2*, said hood protecting the bearings from the accumulation of dust or other foreign substance which might interfere with the free action of the carriage along the track *A'*. This carriage *D* extends downwardly across the open sides of the bearings *3* and is therefore located in front of the track *A'* and bears against the front faces of the balls *4*, said carriage being provided with forwardly-extending arms *6*, one at each end of the platen *B*, and each of these arms *6* is provided with a bearing *7*, open at the top and receiving the adjacent ends of the platen spindle or trunnion *b*. It now appears that the platen *B* is supported in a carriage in front of the bearings *2* and *4*.

and that said carriage is practically suspended from the bearings 2 with a rearward impact against the bearings 4 and that aside from other retaining devices which 5 may be employed to steady the action of the carriage back and forth along the track A' the front end of the carriage is free to be tilted upwardly upon the bearing 2 independently of the oscillatory support A and, 10 in fact, may be lifted bodily, together with the platen, upwardly and away from said bearings and removed from the machine without disturbing the shifting support A.

Any suitable shifting means, not necessary 15 to herein illustrate or describe, may be applied to the oscillatory frame or support A to shift the same vertically, or rather to rock the same upon its pivot a', for the purpose of shifting the carriage D and its platen B vertically to change the position of the latter for 20 printing with upper and lower case type, it being understood that in front-strike machines it is customary to employ two type on each type-bar and that under such circumstances it is necessary to shift either the 25 platen or the type-bars to change from one case type to the other, and, while I have shown and described the specific form of shifting support for the platen, yet I reserve 30 the right to shift the type-bars, if found to be more practical or expeditious.

When the shiftable platen-support is used in the manner described, I provide the oscillatory frame A with a central arm 8, extending 35 downwardly and forwardly under the plate B and terminating at its front end in an elongated yoke 9, extending equal distances at opposite sides of the central arm 8, each end of the yoke being provided with a 40 pair of ears 10, in which are mounted separate pivotal pins 11. Pivotedly mounted upon each pivotal pin is a similar indicator-plate 12, having their lower ends seated between their respective pairs of ears 10 and 45 their upper edges disposed in the same horizontal plane close to the front face of the platen and in a line parallel with the printing-line and a distance below said printing-line substantially equal to half the vertical height 50 of the type, so that the top edges of both index-plates are exactly coincident with the bases of the type. The inner or adjacent edges of these indicator-plates are disposed in parallel vertical lines and are spaced apart 55 a distance corresponding to a certain number, in this instance six type-spaces, and the upper end of each index-plate 12 is provided with graduations 13. Each of the indicator-plates 12 has its lower pivoted end bifurcated 60 for receiving a coil-spring 14, which is mounted upon the pivot 11 and has one end engaged with the yoke 9 and its other end bearing upon the front face of the plate 12, thereby pressing the upper end of said plate 65 lightly toward the platen and against the

paper, which may be wrapped thereon, the upper edges of said plates being deflected rearwardly so as to bear upon the paper in the same straight line parallel with and close to the printing-line. The front ends of the 70 arms 6 of the carriage D are extended forwardly and downwardly and are provided with suitable apertures in which are journaled the opposite ends of a rock-shaft 15, carrying a pair of longitudinally-adjustable 75 paper-holders 16, presently described.

Rigidly secured to one end, preferably the left-hand end of this rock-shaft, is a forwardly-extending finger piece or lever 17, which forms an abutment to prevent end- 80 wise movement to the right, and at the other end of the rock-shaft is rigidly secured a collar 19, which prevents endwise movement of the shaft in the opposite direction. This rock-shaft is preferably angular in cross-section and is provided with a flat front face 85 which is graduated into suitable letter-spaces corresponding with the graduations on the plates 12 and coöperate with the graduations on said plates to determine the 90 position of the printed matter with reference to the printing-point.

Each of the paper-holders 16 is identical in construction, and I will therefore describe only one of them, which consists, essentially, 95 of a strip or band of spring metal having its intermediate portion forming a loop 19, fitted upon the rock-shaft 15 and having one end extended upwardly across and against the flat face of the rock-shaft and terminating in a pair of ears 20, in which is mounted a pivotal pin 21, while the other end is brought forwardly from the rear over the top face of the bar between and in front of the ears 20 and is then deflected upwardly for forming a 100 spring-arm 22, which bears against the front face of a roller-supporting frame 23. The lower end of this roller-supporting frame 23 is formed with an eye pivoted upon the pivotal pin 21, and the opposite longitudinal 105 edges of its upper end are bent forwardly for forming ears 24, in which is mounted a pivotal pin 25, carrying a roller 26, which latter bears upon the periphery of the platen, or 110 rather against the surface of the paper thereon. 115

As best seen in Fig. 1, each of the roller-supporting frames 23 is provided with a central opening 27, having its lower end terminating in a line substantially coincident with or slightly above the upper end of the spring-tongue 22. It will be observed that this spring-tongue 22 normally bears against the front face of the roller-supporting frame 23, thereby pressing said frame rearwardly and holding the roller 26 in engagement with the 120 paper on the platen B, but owing to the fact that the frame 16 is pivoted at its lower end below the upper extremity of the spring-arm 22 the upper end of said frame 16 may be 125 rocked forwardly against the action of the 130

spring 22 until the upper end of the latter enters the opening 27, whereupon the frame 17 may be rocked some distance away from the platen to the position shown in dotted lines, Fig. 3, and the spring-tongue 22 will then pass through the opening 27 and operate to yieldingly hold the frame in its down position. It will also be observed that the loop 19, being of spring metal and fitting closely upon the rock-shaft 15, is held by friction against undue endwise movement, but may be shifted by hand lengthwise of the platen and rock-shaft to any desired position, thereby carrying the roller-supporting frame 23 with it. This roller-supporting frame 23 is pivoted below the printing-line; but its roller 26 is located above the printing-line, and the upper end of the frame 23 is extended above the roller and is bent forwardly a slight distance, forming a finger-engaging portion 28, whereby the upper end of the frame may be rocked to and from its operative position, the spring 22 serving to retain it in either position, and when this roller-supporting frame is rocked to its inoperative position, as shown by dotted lines in Fig. 3, it is clearly evident that the paper or manifold copies in the machine may be readily drawn in either direction to bring them into vertical alinement with the scale on the bar 15, or rather to bring the bases of the printed lines of the paper into registration with the upper edges of the plates 12, or such paper or manifold copies may be shifted lengthwise of the platen to bring any particular letter into registration with one of the graduations 13. In order to further facilitate the "lining-up" of the paper with reference to the printing line or point, I provide each paper-holder with an alining-plate 30, which is made of thin sheet metal having its lower end provided with suitable ears, which are pivoted upon the ends of the pivotal pin 21, the upper edge of said plate 30 being disposed in a straight horizontal line coincident with the upper edges of the plates 12, thereby furnishing alining devices at each end and at the center of the platen by means of which any ruled paper or printed blank forms may be accurately adjusted to the printing-line. The carriage-supporting frame A, and therefore the index-plates 12, are fixed from endwise movement, and as the upper edges of the plates 12 are graduated to correspond with the scale-bar 15 the position of any impression made by the type which strikes midway between the adjacent edges of the plates 12 may be readily determined by comparison with the graduation on the scale-bar 15 midway between the adjacent edges of said plates 12. The plates 30 lie just back of their respective frames 23, and while they are permitted to press lightly against the paper they are prevented from endwise forward displacement by the frames 23, and their lower ends

are provided with forward spring extensions 32, which bear upon the spring-arms 22 in front of the pivots 21, said spring-arms 32 serving to yieldingly force the plates 30 toward the platen and against the paper thereon. In order to hold the rock-shaft 15 and its paper-holding devices 16 in their extreme adjusted positions, I provide the hub of the finger-piece 17 with suitable shoulders or notches 34 and 35, which are engaged by the free end of a spring-detent 36, said detent having its other end secured to the under side of the arm 6 by suitable fastening means, as a screw 37. The opposite faces of the notches 34 and 35 and also the free end of the spring-pawl 36 are beveled in the direction of rotation of the rock-shaft 15 to permit said rock-shaft to be readily turned by means of the hand-piece 17, the free end of the spring engaging in the notch 34 to hold the rock-shaft and its paper-holding devices 16 in their operative positions and also serving to enter the notch 35 to hold the same parts in their inoperative positions. This construction and arrangement of the parts just described enables me to throw both of the paper-holding devices into and out of operative position by the backward or forward movement of the hand-piece 17, or, if desired, the rock-shaft may be left in its normal position and either of the paper-holding devices may be thrown forwardly or backwardly by hand independently of the other.

It will be observed that the outer ends of the central line indicator-plates 12 are curved forward slightly, so that as either of the paper-holding devices approach the printing-point they strike these curved parts and cause them to spring away from the platen, thereby allowing the paper-holders to run under or back of the indicators until the part 22 strikes the lower part of the left-hand plate 12, whereupon the further movement of the carriage causes the paper-holding finger to slide on the bar 15, and thus prevents the finger from passing in front of the printing-point where it might injure the face of the type.

The modifications shown in Figs. 5 and 6 is a somewhat simpler and less expensive construction and comprises a paper-holding finger 16' and a single central indicator-plate 12', the paper holding finger 16' consisting of a spring-frame 23', having its lower end formed with an eye 19', which is closely fitted upon the angular scale-bar 15 and has its central portion formed with a depending spring-tongue 22', which bears upon the front flat face of the rock-shaft or scale-bar 15, thereby holding the paper-holding device 16' yieldingly in its operative position and at the same time permitting said frame to be drawn forwardly by hand, causing the free end of the spring-arm 22' to ride or slide trans-

versely across the flat face of the bar 15 until it rides against the curved lower face of said bar, but when returned to its normal operative position it is frictionally held by contact 5 of the spring-arm 22' with the flat face of the bar 15. Otherwise the construction is very similar to that seen in Fig. 3.

The essential difference of the indicator-plate 12' over that seen in Fig. 1 is that 10 it is formed in a single piece of thin metal having its lower end hinged upon the front end of an arm 8' similar to the arm 8, while its upper end is bifurcated and is provided with opposite graduated parts 13' extending 15 to the graduated parts 13 of the plates 12, the intervening space permitting the operation of the type to and from the platen and also exposing the working part of the inking-ribbon, said plate being held in its operative position by a spring 14' similar to one of the 20 springs 14, Fig. 1.

One of the important objects in mounting the index-plates 13 and 13' upon the forwardly-extending arm of the vertical-shifting carriage-supporting frame, as A, is that these indicator-plates are always shifted vertically with the platen, as distinguished from the ordinary method of securing the index-finger rigidly to the frame of the machine or to a 25 part rigidly connected thereto, in which case the index-finger does not, of course, shift with the platen. This vertical shifting of the indicator-plates is important from the fact that when printing near the end of the sheet there 30 is no liability of the ends of the paper engaging upon and being displaced by engagement with the indicator when the platen is returned 35 after having been shifted.

When it is desired to make an erasure on a 40 number of sheets, as in manifolding, the lever 17 is depressed until the spring 36 engages the notch 35, during which operation both paper-holders 16 are thrown forwardly and are held in this position, thereby enabling 45 the operator to turn back the sheets and make the proper erasures on each sheet without liability of displacing the carbon-sheets or papers, after which the lever and paper-holders are returned to their normal positions 50 and the proper correction made where the erasures occurred, and when an erasure is to be made near the paper-holder on a single sheet it is only necessary to draw that particular holder forward by hand in the manner described and then be returned after the erasure is made.

An important advantage obtained by pivoting the paper-holders below the printing-line and adapting them to be turned to the 60 position shown by dotted lines in Fig. 3 and held in that position is that they are then so far removed from the platen that the holders do not cause the interposed carbon-sheets to smut the work when a number of manifolding sheets are turned forwardly over the holders 65

for the purpose of making erasures on the sheet or sheets next to the platen.

What I claim is—

1. In a front-strike type-writing machine, the combination of a platen-carriage and 70 platen thereon, an oscillatory support having a track for the carriage, an arm rigid on the support and extending forwardly under the platen, and an index finger or plate mounted on the front end of the arm. 75

2. In a front-strike type-writing machine, a laterally-movable carriage, a platen thereon, an oscillating shift-frame supporting the carriage, an arm projecting forwardly from the shift-frame, and an index finger or plate 80 having its lower part pivotally connected to said arm, and its upper part yieldingly held against the platen, and acting to cause the index-finger to retain a fixed relation with the printing-point regardless of the movements of the platen. 85

3. In a front-strike type-writing machine, an oscillatory carriage-supporting frame fixed from endwise movement and having a central forwardly extending arm, a carriage mounted on the frame, a platen supported on the carriage above said arm and a spring-pressed index plate or finger mounted on the arm with its upper edge pressed toward the platen and parallel with the printing-line. 90

4. In a front-strike type-writing machine, an oscillatory carriage-supporting frame having a central forwardly-extending arm, a carriage mounted on the frame, a platen on 100 the carriage and a spring-pressed index plate or finger pivoted to the front end of the arm below the printing-line with its upper edge pressed toward the platen and disposed below and parallel with the printing-line. 105

5. In a front-strike type-writing machine, the combination with a platen, a carriage for the platen, and an oscillating shift-frame for the carriage, of a rod or bar extending parallel with the platen and supported by the carriage below the printing-line, a pair of upright paper-holders slidably mounted on the bar and normally moving therewith, and an index finger or plate located between said paper-holders outside of said bar, and connected to the oscillating shift-frame so as to vibrate therewith without lateral movement. 110

6. In a front-strike type-writing machine, a platen movable laterally and transversely, in combination with a pair of line-indicators operatively connected to move with the platen in both directions, and a central line-indicator operatively connected to move transversely only, the upper edges of all said indicators being arranged in a straight line 115 parallel with, and adjacent to the printing-line. 120

7. In a front-strike type-writing machine, the combination with a platen, and its carriage, of an upright paper-holder in front of 130

- the platen and fulcrumed below the printing-line, a bar forming a support for the paper-holder and extending parallel with the platen, and a spring acting to frictionally secure the paper-holder against accidental movement along the bar, and also acting to press the paper-holder against the platen, or hold it away from the same as required.
8. In a front-strike type-writing machine, the combination with a platen movable axially and transversely of its axis, and a carriage for the platen, of a rock-shaft mounted on the carriage, and a plurality of paper-holders pivotally connected to the rock-shaft, each holder having a spring acting to retain it in either of two positions, the paper-holders being slidable along the rock-shaft and having their pivoted ends connected thereto in a way to cause them to swing to or from the platen with the rocking of the shaft, or to permit the paper-holders to be turned on their pivots to either of the spring-holding positions independent of the movement of the shaft.
- 25 9. In a front-strike type-writing machine, the combination with a platen, a carriage for the platen, and a rock-shaft arranged parallel with the platen, of two paper-holders laterally adjustable on the rock-shaft and pivotally connected thereto, a spring acting to hold each of the paper-fingers in either of two positions, and means for rocking the shaft and holding it in either of two positions.
10. In a front-strike type-writing machine, a platen, and a carriage supporting the platen without obstructing its front and upper side, in combination with an upright paper-holder fulcrumed below the printing-line, a spring acting normally to press the upper part of the holder against the platen, and means acting to hold the paper-holder in a forward position when desired.
- 45 11. In a front-strike type-writing machine, the combination with a platen and its carriage, of a curved paper-holder fulcrumed at its lower end below the printing-line, and means for holding the upper part of the paper-holder upright against the platen above the printing-line, or in a prone position to permit the paper to be turned forward clear from the platen above the printing-line.
- 50 12. In a front-strike type-writing machine, the combination with a platen and its carriage, of a paper-holder fulcrumed at its lower end below the printing-line and extending upwardly and rearwardly over the printing-line, said holder having a pressure-roller fulcrumed between its ends, and a spring normally holding the paper-holder against the platen, or in a downward position when erasures are to be made.
- 55 13. In a front-strike type-writing machine, a platen, in combination with a rock-bar in front of the platen and below the printing-point, paper-holders clamped upon and mov-
- able with the bar to engage the paper above the printing-line, means for rocking the bar, and additional means for holding it in either of its adjusted positions.
14. In a front-strike type-writing machine, a platen and its supporting-carriage, in combination with a rock-shaft mounted upon the carriage parallel with, but below the printing-line, a line-indicator fixed from endwise movement, means to shift the carriage and indicator transversely of the axis of the platen, paper-holders clamped to the bar at opposite sides of the line-indicator and slideable lengthwise of the bar, and additional line-indicators each having operative connection with one of the paper-holders to slide therewith and lengthwise of the paper.
15. In a front-strike type-writing machine, the combination with a platen, and its carriage, of a rod or bar arranged below the printing-line and parallel therewith, and a paper-finger laterally adjustable along said bar having two separate parts bearing against the platen above the rod, one of said parts being movable away from the platen, and means for holding the movable part in either of two positions.
16. In a front-strike type-writing machine, the combination with a platen, and its carriage, of a rod or bar arranged below the printing-line and parallel therewith, and a paper-finger laterally adjustable along said bar having two separate parts both above said rod and terminating one above and the other below the printing-line, with means for holding both parts yieldingly against the platen.
17. In a front-strike type-writing machine, the combination with a platen, of a rod or bar arranged below the printing-line, a line-indicator, and a paper-finger supported by the rod both normally in contact with the platen, and means permitting the paper-finger to swing away from the platen irrespective of the indicator, said rod swinging both the indicator and finger away therefrom as desired.
18. In a front-strike type-writing machine, the combination with a platen, of a rod or bar arranged below the printing-line, a line-indicator and a paper-finger arranged on the rod, the indicator being in rear of the finger, and the finger having an opening through which the indicator can be seen.
19. In a front-strike type-writing machine, the combination with a platen, of a rod or bar arranged below the printing-line, a paper-finger, and a line-indicator arranged on the rod both normally in contact with the platen, and the finger being made to swing forward independently of the indicator and the rod being connected to swing both the finger and indicator forward as desired.
20. In a front-strike type-writing machine, the combination with a shift-carriage, and a

platens, of a supporting-frame having a track for the carriage line-indicators, one at each side of the printing-point supported by the shift-frame whereby it shifts with the platen and is fixed from lateral movement.

21. In a front-strike type-writing machine, the combination with a shift-carriage and a platen, of a carriage-shift frame having a central extension, and a line-indicator sup-

ported by the central extension in front of the platen independently of the carriage.

In witness whereof I have hereunto set my hand this 1st day of June, 1905.

OSCAR C. KAVLE.
